COMPRESSOR AND BALANCING DEVICE
THEREFORWilfrid E. Johnson, Schenectady, N. Y., assignor
to General Electric Company, a corporation of
New York

Application August 9, 1935, Serial No. 35,513

10 Claims. (Cl. 230—58)

My invention relates to compressors of the reciprocating type and balancing devices therefor.

It is frequently necessary to give special consideration to the elimination of unbalanced forces in compressors of various types and especially those used in refrigerating machines. These unbalanced forces set up undesirable vibrations of the machine which are objectionable. In general, the forces to be considered in obtaining balance in an ordinary compressor may be classified as rectilinear and rotating. It has been found to be a comparatively simple matter to counterbalance the rotating forces by the use of ordinary rotating eccentric balance weights. Greater difficulty has, however, been encountered in attempting to eliminate the unbalanced rectilinear forces and especially those set up by the reciprocating piston mechanism of the compressor.

It is an object of my invention to provide an arrangement for exactly balancing the otherwise unbalanced reciprocatory rectilinear forces set up by the piston and associated mechanism of the compressor or the like.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 is a plan view, partly in section, of a Scotch yoke type two-cylinder refrigerant compressor provided with a balancing device embodying my invention; Fig. 2 is a side elevation, partly in section, of the compressor and balancing device shown in Fig. 1; and Fig. 3 is an enlarged perspective view, partly in section, of a portion of the compressor and the balancing device therefor shown in Figs. 1 and 2.

Referring to the drawing, I have shown in Fig. 1 a two-cylinder Scotch yoke type refrigerant compressor including a cylindrical cross yoke 10 and a pair of axially aligned oppositely acting cylindrical pistons 11 and 12 which are rigidly secured to opposite sides of the cross yoke 10 and arranged at right angles thereto. The pistons 11 and 12 reciprocate in coaxial cylinder bores formed in cylinders 13 and 14, respectively, which are secured by bolts 16 to the top of the frame of an electric driving motor 15. The compressor is driven by the rotating shaft 17 of the electric motor 15 through a crank 18, the upper end of which is journaled in a cylindrical block 19 slidably fitted in the cross yoke 10. The lower side

of the cross yoke 10 is provided with an elongated slot 20 through which the crank 18 passes. The rotary motion of the crank 18 causes the pistons 11 and 12 to reciprocate in the cylinders 13 and 14 with a consequent reciprocation of the block 19 in the cross yoke 10 at right angles with respect to the axis of the pistons 11 and 12.

The outer ends of the cylinders 13 and 14 are closed by rectangular muffle boxes 21 and 22, respectively, which are secured thereto by screws 10 23 and 24. The muffle boxes 21 and 22 contain suitable valve mechanisms for the compressor, and gaseous refrigerant is supplied to the interior of the cylinders 13 and 14 through intake conduits 25 and 26, respectively. The gaseous refrigerant 15 compressed in the cylinders 13 and 14 by the pistons 11 and 12 is discharged therefrom through suitable valves and exhaust conduits 27 and 28, respectively.

The unbalanced rotating forces set up by the eccentrically located crank pin 18 and slide block 19 are balanced by suitable rotating eccentric counterbalance weights, one of which is shown at 29 and which is segmental in shape. The couples set up between the balance weight 29 and the 25 crank pin 18 and the slide block 19 are balanced by the second balance weight secured to the lower portion of the shaft 17 (not shown), the lower weight being positioned 180° about the shaft from the upper weight 29.

A plurality of inertia members are provided for exactly balancing the rectilinear forces set up by the reciprocatory motion of the pistons 11 and 12 and the driving mechanism therefor. In the illustrative form of my invention, a pair of duplicate 35 segmental balance weights 30 and 31 are utilized as the inertia members. The balance weights 30 and 31 are pivotally mounted for oscillatory movement through arcs of less than 180° in a horizontal plane at right angles to the axis of 40 the motor shaft 17 on stationary pivot pins 32 and 33, respectively, which pass through the centrally located bores in the hubs 34 and 35 of the balance weights 30 and 31. The balance weights 30 and 31 are symmetrically positioned on opposite sides of 45 the axis of the pistons 11 and 12. It will be noted that the balance weights 30 and 31 are symmetrical about a vertical plane of symmetry bisecting the angle of the segmental upper surfaces thereof. This plane of symmetry is also the vertical plane 50 of symmetry of inwardly extending links 36 and 37. The lower ends of the pins 32 and 33 are rigidly supported, preferably on the top of the end shield of the electric motor 15. The balance weights 30 and 31 are so connected to the pistons 55

that the balance weights are accelerated in such manner that the component of movement thereof parallel to the axis of the pistons 11 and 12 is in a direction opposite to the direction of movement of the pistons and that the rate of acceleration in such direction is exactly proportional to the rate of acceleration of the pistons. It is of prime importance that the rates of acceleration of the pistons and balancing mechanism should be opposed and exactly proportional in order that the forces set up by each shall at all times be equal and opposite. In the illustrative form of my invention, the balance weights 30 and 31 are provided with the inwardly extending links 36 and 37 which are integral with the inner sides of the hubs 34 and 35, respectively. The inner ends of the links 36 and 37 are provided with cylindrical guide blocks 38 and 39. Square holes 40 and 41 are broached or otherwise formed in the centers of the cylindrical guide blocks 38 and 39, respectively, and the inner ends of the links 36 and 37 extend within these holes. Pins 42 and 43 having their opposite ends journaled in holes 44 and 45 in the guide blocks 38 and 39 extend through holes 46 and 47 in the inner ends of the links 36 and 37, thus, pivotally connecting the links and guide blocks. The guide blocks 38 and 39 are slidably supported in a cylindrical cross guide 48 which is welded, or otherwise rigidly secured, to the top of the cross yoke 10 in axial alignment therewith as indicated at 49. Since the cross guide 48 in which the guide blocks 38 and 39 reciprocate is rigidly secured to the cross yoke 10 of the piston mechanism, displacement of the inner ends of the links 36 and 37 axially of the pistons 11 and 12 is prevented.

The balance weights 30 and 31 are designed to balance out all of the unbalanced reciprocatory forces set up by the entire piston mechanism which in the illustrative form of my invention is made up of the pistons 11 and 12, the yoke 10 and the cross guide 48. Since the length of the links 36 and 37 between the pivots at the opposite ends thereof is fixed and since the distance between the centers of the pivots 32 and 33 and the centers of the weights 30 and 31 is also fixed, the displacement of a point on the plane of symmetry of the weights 30 and 31 along a component of motion parallel to the motion of the piston mechanism will always be exactly proportional to the displacements of the piston mechanism. As a consequence, the acceleration of the weights 30 and 31 in a direction parallel to the line of motion of the piston mechanism will always be exactly proportional to the acceleration of the piston mechanism but in an opposite direction.

The oscillating balance weights 30 and 31 are so designed with respect to the reciprocating piston mechanism that no unbalanced couples about any horizontal axis will appear in the completed system. This result may conveniently be accomplished by individually designing each of the balance weights in such manner that the product of inertia of each weight about an axis lying in a horizontal plane passing through the center of gravity of the piston mechanism and about a vertical axis passing through the center of the pivotal support of the balance weight are equal to zero, each of the axes lying in the vertical plane of symmetry of the balance weight. This relation of the products of inertia of the balance weights may be expressed mathematically by the equation:

$$G = \Sigma mxy = 0$$

75 Where G represents the product of inertia of the

balance weight, m is the mass of an infinitesimal particle of the balance weight, and x and y are the position co-ordinates of the particle with respect to a pair of co-ordinate planes. One of the co-ordinate planes is a horizontal plane passing through the center of gravity of the piston mechanism and the other is the vertical plane of symmetry of the balance weight.

It should be noted that it is not necessary that the balance weights 30 and 31 be arranged in such manner that their centers of gravity lie in the same horizontal plane as the center of gravity of the piston mechanism. In fact, such an arrangement may result in unbalanced couples tending to cause vibratory movement of the compressor. As pointed out, however, it is necessary that the product of inertia of each of the balance weights about a vertical axis passing through the pivot support of the balance weight and a horizontal axis lying in a plane passing through the center of gravity of the piston mechanism, the axes lying in the vertical plane of symmetry of the balance weight, be equal to zero. Such an arrangement is particularly useful in refrigerant compressors of the type illustrated, since it may be necessary or at least desirable to locate the balance weights 30 and 31 above the plane of the pistons 11 and 12 in order to provide suitable space for the cylinder and other compressor mechanism.

The balance weights 30 and 31 are preferably made segmental in shape as illustrated and are provided with outwardly extending flanges 30a and 31a along the upper edges thereof. This shape is preferable in that it lends itself to a convenient form for the theoretical calculation of the necessary distribution of weight. After the balance weights 30 and 31 have been made in accordance with their calculated design, the distribution of weight may be checked experimentally. In order to determine experimentally the exact weight distribution required, one of the balance weights complete with its link is mounted on a pivot passing through the hub thereof. A weight is then rigidly attached to the inner end of the link of the balance weight, this attached weight being exactly equal to one-half the weight of the piston mechanism. It will be understood that by the term "piston mechanism" the pistons 11 and 12 are included, as well as the cross yoke 10 and the cross guide 48. The center of gravity of this weight must be placed exactly below the center of the pivot pin hole formed in the inner end of the link and in the plane of the center of gravity of the piston mechanism. The balance weight is then rotated on its pivotal support and portions of the same may be removed from the periphery of the main body of the weight or from the side of the flange formed on the upper edge thereof until a true dynamic balance is obtained. The other weight may then be similarly balanced. When the weights have been dynamically balanced in the manner described, the product of inertia of each balance weight about a vertical axis passing through the pivotal support thereof and a horizontal axis lying in the plane of symmetry of the balance weight and the plane of the center of gravity of the piston mechanism will be equal to zero.

In the arrangement illustrated, the oscillatory movement of the balance weights 30 and 31 may be resolved into two components, one component lying parallel to the line of movement of the pistons 11 and 12, and the other component at right angles thereto. Since the components of

75

movement of the balance weights 30 and 31 at right angles to the line of movement of the pistons 11 and 12 are exactly equal and opposite at all times, the horizontal forces set up in the direction of these components are exactly balanced. Since the components of the movement of the balance weights 30 and 31 parallel to the line of movement of the piston mechanism are always in a direction opposite to the movement of the latter, and since the acceleration of the balance weights parallel to the piston mechanism is always proportional to the acceleration of the piston mechanism, the horizontal forces set up by the piston mechanism are always balanced by the balance weights. As pointed out above, the balance weights 30 and 31 are designed in such manner that the product of inertia of each of the weights about a vertical axis passing through the pivotal support thereof and a horizontal axis 20 lying in the plane of the center of gravity of the piston mechanism, each of the axes lying in the plane of symmetry of the balance weight, are equal to zero, and as a consequence no unbalanced couples about any horizontal axis will appear in the system. It will thus be seen that I have provided a balance arrangement in which all of the rectilinear forces in the compressor are exactly balanced.

The balancing arrangement which I have provided is particularly advantageous in connection with a two-cylinder compressor in that it tends to smooth out the torque curve of the crank shaft. In the case of a two-cylinder compressor, such as the one illustrated, when the compressor pistons are moved from the extreme position shown in Fig. 1 to the opposite extreme position, the crank shaft turns through an arc of 180°. During the first part of this movement, the piston 11 will be moving on its intake stroke while the piston 12 is just beginning its compression stroke. As a consequence, a comparatively small torque is required to turn the crank shaft during the first 90° of the half revolution noted. During the second 90° of the half revolution, the piston 12 exerts its maximum compressive force and a comparatively greater torque is required. During the first 90° of this movement, however, the inertia of the balance weights 30 and 31 oppose the movement of the crank shaft, while during the second 90° of such movement the inertia of the balance weights, which are also moving through the second portion of their arc of movement, aids the movement of the crank shaft. As a consequence, even though the motion of the balance weight is of the same frequency as the pistons, double frequency torque is applied to the crank shaft which is opposite in phase to what is in effect a double frequency torque caused by the compression in the cylinders. The torque curve of the crank shaft is thus smoothed out appreciably.

While I have shown a particular embodiment of my invention in connection with a Scotch yoke type refrigerating machine compressor, I do not desire my invention to be limited to the particular construction shown and described and I intend, in the appended claims, to cover all modifications within the spirit and scope of my invention.

What I claim as new and desire to secure by Letters Patent of the United States is:

1. A reciprocating type compressor and balancing device therefor comprising a reciprocatable piston, a plurality of inertia members, means including a plurality of pivots stationary with re-

spect to the compressor for pivotally supporting said inertia members on opposite sides of the axis of said piston for oscillatory movement in an arc of less than 180°, and means including links connecting said inertia members and said piston for oscillating said inertia members about said stationary pivots and for accelerating said inertia members in such oscillatory movement with a component of movement in a direction opposite to the direction of movement of said piston and at a rate of acceleration in the direction of said component exactly proportional to the rate of acceleration of said piston. 5

2. A reciprocating type compressor and balancing device therefor comprising a pair of axially aligned and oppositely acting pistons, a pair of inertia members, means including a plurality of pivots stationary with respect to the compressor for pivotally supporting said inertia members on opposite sides of the axis of said pistons and symmetrically with respect to said axis for oscillatory movement in an arc of less than 180°, and means including links connecting said inertia members and said pistons for oscillating said inertia members about said stationary pivots and for accelerating said inertia members in such oscillatory movement with a component of movement in a direction opposite to the direction of movement of said pistons and at a rate of acceleration in the direction of said component exactly proportional to the rate of acceleration of said pistons. 15 20 25

3. A reciprocating type compressor and balancing device therefor comprising a reciprocatable piston mechanism, a pair of inertia members, means for pivotally supporting said inertia members on opposite sides of the axis of said piston and symmetrically with respect to said axis for oscillatory movement in an arc of less than 180° links rigidly connected to each of said inertia members and extending therefrom toward the axis of said piston, and means for preventing displacement of the inner ends of said links axially of said piston, the inner ends of said links being free to move at right angles with respect to the axis of said piston. 35 40 45

4. A reciprocating type compressor and balancing device therefor comprising a reciprocatable piston, a pair of inertia members, means for pivotally supporting said inertia members on opposite sides of the axis of said piston and symmetrically with respect to said axis for oscillatory movement in an arc of less than 180°, links rigidly connected to each of said inertia members and extending therefrom toward the axis of said piston, guide blocks pivotally connected to each of said links, and means for preventing displacement of each of said guide blocks axially of said piston, said guide blocks being free to move at right angles with respect to said axis of said piston. 50 55 60

5. A reciprocating type compressor and balancing device therefor comprising a reciprocatable piston, a pair of inertia members, means for pivotally supporting said inertia members on opposite sides of the axis of said piston and symmetrically with respect to said axis for oscillatory movement in an arc of less than 180°, links rigidly connected to each of said inertia members and extending therefrom toward the axis of said piston, guide blocks pivotally connected to each of said links, and means including a cross guide rigidly carried by said piston and positioned at right angles to the axis thereof and adapted to receive said guide blocks for preventing displacement of said guide blocks axially of said piston, 65 70 75

said guide blocks being free to move in said cross guide at right angles to the axis of said piston.

6. A reciprocating compressor of the Scotch yoke type and balancing device therefor comprising a reciprocatable piston, a cross yoke rigidly secured at right angles thereto, a pair of inertia members, means for pivotally supporting said inertia members on opposite sides of the axis of said piston and symmetrically with respect to said axis for oscillatory movement, links rigidly connected to each of said inertia members and extending inwardly therefrom toward the axis of said piston, guide blocks pivotally connected to each of said links, and means including a cross guide rigidly connected to said cross yoke in axial alignment therewith and adapted to receive said guide blocks for preventing displacement of said guide blocks axially of said piston, said guide blocks being free to move in said cross guide at right angles to the axis of said piston.

7. A reciprocating compressor of the Scotch yoke type and balancing device therefor comprising a cross yoke, a pair of axially aligned pistons rigidly secured to said cross yoke on opposite sides thereof, a pair of inertia members, means for pivotally supporting said inertia members on opposite sides of the axis of said pistons and symmetrically with respect to said axis for oscillatory movement, links rigidly connected to each of said inertia members and extending inwardly therefrom toward the axis of said pistons, guide blocks pivotally connected to each of said links, a cross guide integral with said cross yoke in axial alignment therewith and adapted to receive said guide blocks for preventing displacement of said guide blocks axially of said pistons, said guide blocks being free to move in said cross guide at right angles to the axis of said pistons.

8. A reciprocating type compressor and balancing device therefor comprising a piston mechanism including a pair of axially aligned and oppositely acting pistons, a pair of inertia members having a vertical plane of symmetry, means including a plurality of pivots stationary with respect to the compressor for pivotally supporting said inertia members on opposite sides of the axis of said pistons and symmetrically with respect to said axis for oscillatory movement in an arc of less than 180°, the product of inertia of each of said inertia members about a pair of axes lying in said plane of symmetry being equal to zero, one of said axes being vertical and passing through the center of said pivotal support of said member and the other of said axes lying in a horizontal plane and passing through the center of gravity of said piston mechanism, and means including links connecting said inertia members and said pistons for oscillating said inertia members about said stationary piv-

ots and for accelerating said inertia members in such oscillatory movement with a component of movement in a direction opposite to the direction of movement of said pistons and at a rate of acceleration in the direction of said component exactly proportional to the rate of acceleration of said pistons.

9. A reciprocating type compressor and balancing device therefor comprising a reciprocatable piston mechanism, a pair of inertia members having a vertical plane of symmetry, means for pivotally supporting said inertia members on opposite sides of the axis of said piston mechanism and symmetrical with respect to said axis for oscillatory movement in an arc of less than 180°, the product of inertia of each of said inertia members about a pair of axes lying in said plane of symmetry being equal to zero, one of said axes being vertical and passing through the center of said pivotal support of said member and the other of said axes lying in a horizontal plane and passing through the center of gravity of said piston mechanism, links rigidly connected to each of said inertia members and extending therefrom toward the axis of said piston mechanism, and means for preventing displacement of the inner ends of said links axially of said piston mechanism, the inner ends of said links being free to move at right angles with respect to the axis of said piston mechanism.

10. A reciprocating compressor of the Scotch yoke type and balancing device therefor comprising a piston mechanism including a cross yoke, a pair of axially aligned pistons rigidly secured to said cross yoke on opposite sides thereof, a cross guide integral with said cross yoke in axial alignment therewith, said balancing device including a pair of inertia members having a vertical plane of symmetry, means for pivotally supporting said inertia members on opposite sides of the axis of said pistons and symmetrically with respect to said axis for oscillatory movement, a product of inertia of each of said inertia members about a pair of axes lying in said plane of symmetry being equal to zero, one of said axes being vertical and passing through the center of said pivotal support of said inertia member and the other of said axes lying in a horizontal plane and passing through the center of gravity of said piston mechanism, links rigidly connected to each of said inertia members and extending inwardly therefrom toward the axis of said pistons, guide blocks pivotally connected to each of said links and slidably mounted in said cross guide, said guide blocks being free to move in said cross guide only at right angles to the axis of said pistons.

WILFRID E. JOHNSON.
